CLAIM

The ornamental design for a portion measuring insert
for a container or the like, substantially as shown and
described.

DESCRIPTION

FIG. 1 is a perspective view of a portion measuring
insert for a container or the like showing my new design
with a container being shown in broken lines to illus-
trate environmental use only;

FIG. 2 is an enlarged, fragmentary view showing the
left end of FIG. 1;

FIG. 3 is a top plan view;

FIG. 4 is a bottom plan view; and

FIG. 5 is a cross-sectional view taken along line 5—5 of
FIG. 3.
